UNITED STATES PATENT OFFICE.

HARRY H. KLEIN, OF NEW YORK, N. Y.

WEIGHTED TAPE.

1,053,405.

Specification of Letters Patent. Patented Feb. 18, 1913.

Application filed November 2, 1911. Serial No. 658,101.

To all whom it may concern:

Be it known that I, HARRY H. KLEIN, a citizen of the United States, residing in New York city, in the county of New York and State of New York, have invented certain new and useful Improvements in Weighted Tapes, of which the following is a specification.

This invention relates to weighted tapes 10 of the class used by dressmakers and tailors for assisting in the construction and draping of skirts, cloaks, and other articles of apparel; whereby such articles are caused to hang with uniformity and without wrinkling, and to remain in desired position 15 while in use.

The principal object of the invention is to provide a tape with a series of weights therein at spaced intervals that can be easily 20 and quickly secured in proper position in the tape, and without the use of stitching or other laborious operation.

In the accompanying drawing, showing one embodiment of my invention, Figure 1 25 is a transverse section on the line 1—1 of Fig. 2, and Fig. 2 is a plan view of a portion of a tape indicating the weights in position and the fastening means.

The tape member 2 may be of any desired 30 form or construction, and is shown as comprising a pair of tapes 3 and 4 that are suitably secured together at their margins such as by stitching along the lines 5 and 6. This will form a substantially tubular member 35 leaving an interior closed space 7 therebetween.

At suitable spaced intervals along the tape member, weights such as 8, 9 and 10 are provided. These may be of any suitable or desired form, being shown as comparatively 40 flat and of rectangular outline. These weights are provided with one or more apertures preferably at the center, and two apertures are shown in each of the weights that are disposed transversely of the 45 weights, or extending across their narrower dimension. These weights are secured to one of the tapes, such as the tape 4, by eyelets, such as a dual or twin eyelet 11, as shown. This eyelet may extend entirely 50 through the aperture in the weight and through the tape member 4, with each end spread outwardly or clenched. By this means each weight is securely fastened to the tape member, and at the same time no 55 projecting portion is provided that would interfere in any way with the fabric of the garment.

Having thus described my invention, I 60 claim:

A tubular tape, a series of apertured weights at spaced intervals along the tape at the inside portion thereof, and eyelets passing through the apertures of the 65 weights and through the tape whereby the weights are secured to the tape.

HARRY H. KLEIN.
